FIG. 1

FIG. 2

To all whom it may concern:

Be it known that we, Donald V. Vesely, Robert J. Besal, and Thomas J. Gresch, have invented a new, original, and ornamental Design for Outdoor Lighting Fixture, of which the following is a specification, reference being had to the accompanying drawing, forming a part thereof.

Fig. 1 is a perspective view showing an end and the top of an outdoor lighting fixture embodying our new design; and

Fig. 2 is a perspective view showing the other end and the bottom of the fixture.

The broken lines shown in the drawing are for illustrative purposes only.

We claim:

The ornamental design for an outdoor lighting fixture, as shown and described.
